UNITED STATES PATENT OFFICE.

CHARLES O. LYDICK, OF DES MOINES, IOWA.

LOCKING DEVICE FOR GATE-OPERATING MECHANISM OR THE LIKE.

1,413,674.

Specification of Letters Patent Patented Apr. 25, 1922.

Application filed March 28, 1921. Serial No. 456,324.

To all whom it may concern: Be it known that I, CHARLES O. LYDICK, a citizen of the United States, and a resident of Des Moines, in the county of Polk and

5 State of Iowa, have invented a certain new and useful Locking Device for Gate-Operating Mechanism or the like, of which the following is a specification.

The object of my invention is to provide a locking device for a gate operating mechanism or the like, which is of simple, durable and inexpensive construction.

My invention is illustrated in connection with a gate supported on an over-head track, 10 and adapted to be operated from a point on either side of the gate so that the gate may be moved to open or closed position without the necessity of the driver of the vehicle, or the like, from getting out thereof.

20 More particularly my object is to provide in such a device a means for locking the gate against movement in either direction so that it will be impossible for cattle or other animals from accidentally moving the gate to open position.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which:

Figure 1 is a side elevation of my improved gate and locking device, the gate being shown in its open position.

Figure 2 is a central, vertical, sectional view taken on the line 2—2 of Figure 1.

Figure 3 is an enlarged, detail view of the locking device.

Figure 4 is a sectional view taken on the line 4—4 of Figure 3, parts being removed to better illustrate the construction and showing the locking device in its closed position.

Figure 5 is a sectional view taken on the line 5—5 of Figure 4 showing the side flanges adjacent to the rack bar device; and

Figure 6 is a sectional view taken on the line 6—6 of Figure 1.

In the accompanying drawings I have used the reference numeral 10 to indicate an ordinary barbed wire fence and 11 to indicate a short post to which the barbed wire is fixed.

A pair of posts 12 are provided to which

the barbed wire 10 is also fixed, and which extend upwardly a considerable amount above the fence line. An over-head track 13 is fixed to the post 12 and is supported thereby. A gate 14 having the upwardly extending arms 15 thereon is suspended from the track 13.

A pair of grooved pulley wheels 16, mounted on the short shaft 17 in the arms 15 serve as guides for holding the gate suspended from the track 13.

One of the posts 12 is provided with a pair of plates 18 which have their forward ends received between the plates 18 when it is in its closed position, and will prevent the gate from swinging or other undesired movement.

On each side of the gate, and adjacent to one side of the drive way for which the gate is used, I have provided pairs of supports 20 in which is journalled a shaft 21 having a gear 22 fixed thereon intermediate of its ends.

Each of the ends of the shaft 21 are bent 80 so as to provide the handle or crank 23.

It will be seen that by raising of the handle 23 the gear 22 will be caused to rotate. The upper edge of the gate 14 is provided with a rack bar 24 which is in mesh with the gear 22.

Upon each side of the rack bar 24, and partially receiving the lower edge of the gear 22 are the plates 25 which serve as guides for holding the gear in engagement with the rack bar and preventing the parts from becoming out of alignment.

From the parts just described it will be seen that rotation of the shaft 22 will cause the gate 14 to be moved on the track 13 for causing the gate to either be opened or closed as the case may be.

It will be understood that the handles 23 are far enough away from the gate so that a party desiring to open the gate may drive up with his car, and reach out and engage the handle for opening the gate. The party then drives through the drive way and stops at the handle on the opposite side of the gate; by rotating this second handle in the opposite direction it will cause the gate to be moved to closed position.

In order to lock the gate against accidental opening I have provided a locking device which engages the gear 22 and prevents the rotation thereof.

In order to accomplish this, I place a beam

26 upon the upper ends of the supports 20 as illustrated in Figure 2 of the drawings. Upon the beam 26 are mounted the brackets 27 which are provided with openings for 5 forming a bearing for the shaft 28.

The shaft 28 at its center and directly above the gear 22 is provided with a crank portion 29. A plate 30 is mounted on a portion of the beam 26 and is provided with an 10 opening 31 which registers with an opening 32 in the beam 26.

A lever 33 which has a slot 34 therein is pivoted upon the bracket 35 at 36. The crank portion 29 of the shaft 28 is received 15 within the slot 34 and capable of sliding movement therein.

A locking pawl 37 is pivoted to the free end of the lever 33 and extends through the openings 31 and 32 directly above the 20 gear 22.

The locking pawl 37 is designed to engage the teeth of the gear 22; and has its lower end slightly tapered so as to permit it to easily engage the teeth of the gear 22. 25

When the locking device is in the position shown in Figure 4 of the drawings it will be impossible to rotate the gear 22, thus preventing of the opening or closing of the gate.

30 In order to control the locking device when it is desired to open the gate, I have arranged arms 38 on the ends of the shaft 28. A weight 39 is mounted on the ends of the arms 38.

35 When the arms 38 are swung to the position shown in dotted lines in Figure 4, then the locking pawl 37 is out of engagement with the gear 22. The gate tends to hold the locking pawl either in engagement or out of 40 engagement with the teeth of the gear 22.

The raising and lowering of the locking pawl is accomplished by the crank portion 29 on the shaft 28.

45 It will be understood that the locking device is operated just before the gate is opened and after it is closed. In this way the gate can only be opened by doing the positive

act, by moving the arm 38 and the weight 39 to the position where the locking pawl will be out of engagement. 50

It will be seen that the parts of my device are very simple and that the gate can be easily opened and closed, and that it is very simple to lock the gate by a device controlled at a point adjacent to the handles, 55 which are used for moving the gate to open or closed position.

The advantage of the locking device can readily be seen since it insures at all times the holding of the gate in its locked position; when the locking pawl is in engagement with the gear 22 it is impossible to move the gate, yet the parts are so arranged that it is very easy to move the locking pawl to open position, this being accomplished by 65 swinging the arm 38.

Some changes may be made in the construction and arrangement of the details of my device, without departing from the real spirit and purpose of my invention, and it 70 is my intention to cover by my claim, any modified forms of structure or use of mechanical equivalents, which may be reasonably included within their scope.

I claim as my invention: 75

A lock for a closure having a co-operating rack and pinion, comprising a shaft designed to be above and parallel with the rotating axis of the pinion, having an upwardly inclined weighted arm, a vertical, 80 slideable pawl, designed to be above such pinion, a slotted guide for said pawl, a lever pivotally supported between its ends and having one end pivoted to said pawl, a crank on said shaft having a pivotal and sliding 85 connection with the other end of said lever, whereby when the weighted arm is swung over center in one direction, the pawl will be held, thereby, in engagement with the pinion, whereas when the arm is swung over 90 center in the other direction, the pawl will be held free from the pinion.

Des Moines, Iowa, December 9, 1920.

CHARLES O. LYDICK.
